UNITED STATES PATENT OFFICE

2,184,653

BURNER FOR GASEOUS OR LIQUID FUEL

Samuel T. Sherrick and Charles A. Lewallen,
Denver, Colo., assignors to Vac-Q-O Burner
and Oil Cleaner Company Incorporated

Application March 13, 1939, Serial No. 261,566

2 Claims. (Cl. 158—99)

This invention relates to a burner for use with gas or oil and has for its principal object the provision of a small, simple, compact unit which will deliver a maximum amount of heat from a minimum amount of fuel and which will be smokeless, noiseless, and odorless when in use.

The invention is more particularly designed for heating buildings but is not limited to this particular use as it will be found valuable wherever a maximum heat is desired from a relatively small, portable device.

Another object of the invention is to so construct the burner that it may be used within any standard stove, furnace or fireplace, or independent thereof as desired.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a vertical section through the improved burner.

Figs. 2 and 3 are horizontal cross sections therethrough, taken on the lines 2—2, and 3—3, respectively.

The improved burner consists of an outer housing 10 having a cylindrical air thimble 11 extending upwardly from and opening concentrically through the bottom thereof. A cylindrical jacket 12 extends downwardly into the housing 10 terminating above the bottom thereof and provided with an inwardly turned flange 13 extending to and enclosing the thimble 11. The flange 13 is preferably welded to the thimble 11 to support the jacket 12. The jacket 12 contains three series of perforations; a lower series of fuel perforations 17; a primary air series 18; and a secondary air series 19.

The top of the housing is formed with a downwardly inclined flange plate 14 which terminates in spaced relation to the jacket 12 to form an annular, down-draft throat 15. The throat 15 may be closed when desired by means of a vertically slidable valve ring 16 having a tapered face for sealing the throat 15.

A perforated air distributing sleeve 20 is slidably fitted into the upper extremity of the thimble 11 and supports a flame spreading ring 21 of fire clay or similar refractory, heat-resistant

material. A central air flue 22 is supported on the ring 21. The air flue is closed at its top by means of a flame spreading cap member 23 also of refractory, heat-resisting material. A series of perforations 24 surround the upper extremity of the air flue 22.

Fuel is fed to the burner through a suitable fuel pipe 25 leading to a perforated distributing ring 26 in the bottom of the housing 10. The distributing ring 26 is embedded in a layer of porous, fire-resisting material, preferably in a loose bed of exfoliated vermiculite 27. The fuel discharging from the ring 26 spreads throughout the entire porous bed of vermiculite so as to rise from the entire upper surface thereof.

If gas is used for fuel, it rises from this bed into the housing 10 where it is met by a down draft from the throat 15. The mixed air and fuel flows through the lower fuel perforations 17 into the bottom of the jacket 12 where it is ignited. The flames rise upwardly in the jacket taking or additional combustion air as they pass the sleeve perforations and the primary perforations 18. Any unburned gas remaining will be mixed with air through the perforations 24 and finally through the secondary perforations 19 so that complete combustion of all of the gas is had.

If oil is used for fuel, the device is preheated to gasify the fuel in the housing so that the fuel gas will flow through the perforations 17 and through the mixing and burning stages similarly to the previously described gas fuel. The rising volume of burning gases in the jacket creates a partial vacuum in the housing 10 to prevent combustion therein and to draw in the primary air through the down draft throat 15. If this throat be closed by means of the valve ring 16, combustion will immediately cease.

Where intense heat is desired, additional air may be introduced into the housing, there being a plugged pipe opening 28 for this purpose. A second plugged pipe opening 29 may be used for additional gas, oil, or water. The housing 10 is formed with suitable legs 30 for supporting it above the floor or other surface to allow the air to enter the thimble 11.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A burner comprising: an outer cylindrical housing; a cylindrical jacket of less diameter

than said housing supported therein and extending; an annular inwardly extending flange at the upstanding thimble within said jacket, opening through the floor of said housing; a flue extending upward from said thimble within said housing; an annular inwardly extending flange at the top of said housing terminating in spaced relation to said jacket to leave an annular down draft throat; and a flame spreader supported by said flue within said jacket, there being perforations in said jacket within said housing and above the latter and perforations in said flue above and below said flame spreader; and means for supplying fuel to said housing exteriorly of said jacket.

15 2. A burner comprising: an outer cylindrical housing; a cylindrical jacket of less diameter than said housing supported therein and extending upwardly above the top of said housing; an

upstanding thimble within said jacket opening through the floor of said housing; a flue extending upward from said thimble within said housing; an annular inwardly extending flange at the top of said housing terminating in spaced relation to said jacket to leave an annular down draft throat; and a flame spreader supported by said flue within said jacket, there being perforations in said jacket within said housing and above the latter and perforations in said flue above and below said flame spreader; a bed of flocculent fire resisting material in the bottom of said housing; means for feeding fuel to said bed; and means for supporting said housing above a supporting surface.
